CLAIM

The ornamental design for a foldable hand truck as shown and described.

DESCRIPTION

FIG. 1 is a left, front and top perspective view of a foldable hand truck showing my new design;

FIG. 2 is a right, rear and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof;

FIG. 9 is a perspective view thereof, showing the handle of foldable hand truck in a tilted configuration; and,

FIG. 10 is a perspective view thereof, showing the foldable hand truck in a folded configuration.

The evenly spaced broken lines depict portions of the foldable hand truck that form no part of the claimed design.

1 Claim, 10 Drawing Sheets
